(57) **CLAIM**

The ornamental design for a bird waterer, as shown and described.

DESCRIPTION

FIG. 1 is a front, right and top perspective view of a bird waterer showing a first embodiment of my new design.

FIG. 2 is a rear, right and bottom perspective view thereof.

FIG. 3 is a front view thereof.

FIG. 4 is a rear view thereof.

FIG. 5 is a right side view thereof.

FIG. 6 is a left side view thereof.

FIG. 7 is a top view thereof.

FIG. 8 is a bottom view thereof.

FIG. 9 is a front, right and top perspective view of a bird waterer showing a second embodiment of my new design.

FIG. 10 is a rear, right and bottom perspective view thereof.

FIG. 11 is a front view thereof.

FIG. 12 is a rear view thereof.

FIG. 13 is a right side view thereof.

FIG. 14 is a left side view thereof.

FIG. 15 is a top view thereof; and,

FIG. 16 is a bottom view thereof.

The broken lines illustrate environmental structure that forms no part of the claimed design. The bird waterer is shown with a symbolic break in its length, represented by break lines. The appearance of any portion of the article between the symbolic break lines forms no part of the claimed design.
